(57) **CLAIM**

The ornamental design for a torch holding device, as shown and described.

DESCRIPTION

FIG. 1 is a front elevational view of the torch holding device of the present invention;

FIG. 2 is a rear elevational view of the torch holding device of FIG. 1;

FIG. 3 is a left side elevational view of the torch holding device of FIG. 1, the right view being a mirror image thereof;

FIG. 4 is a top plan view of the torch holding device of FIG. 1;

FIG. 5 is a bottom plan view of the torch holding device of FIG. 1; and,

FIG. 6 is a top, front, right side perspective view of the torch holding device of FIG. 1.

The broken lines showing of a torch, railing and bolts in FIG. 6 are for illustrative purposes only and form no part of the claimed design.
